UNITED STATES PATENT OFFICE.

CARL MARTINI, OF BERLIN, GERMANY; MARIA MARTINI, OF HANOVER, GERMANY, EXECUTRIX OF SAID CARL MARTINI, DECEASED, ASSIGNEE TO MARTINI & HÜNEKE MASCHINENBAU-AKTIEN-GESELLSCHAFT, OF BERLIN, GERMANY, A CORPORATION OF GERMANY.

TESTING AND CONTROLLING DEVICE FOR PRODUCERS OF INERT GASES.

1,099,611.

Specification of Letters Patent.

Patented June 9, 1914.

Application filed September 9, 1908. Serial No. 516,876.

To all whom it may concern:

Be it known that I, CARL MARTINI, a subject of the German Emperor, and resident of Berlin, Germany, have invented certain new and useful Improvements in Testing and Controlling Devices for Producers of Inert Gases, of which the following is a specification.

My invention relates to the production of inert gases suitable for the protection of inflammable liquids (say, gasolene) contained in tanks or receptacles from which air is excluded. I have produced such an inert gas by the combustion of a mixture of air and inflammable gas or vapor in a closed chamber to which no additional air is admitted. In the practical operation of the apparatus it is of advantage to provide means for testing whether or not the mixture fed to the producer has the proper constitution. This I accomplish, according to one feature of the present invention, by introducing a portion of such mixture into an internal combustion engine, as the working medium therefor. Should the gaseous mixture become unsuitable, the engine will stop, thus calling attention to the fact that the apparatus is not working properly.

According to another feature of my invention, the heat of the producer of inert gases is utilized to control the operation and particularly the ignition of the tell-tale engine.

A further feature of my invention has for its object to insure the supply of a properly proportioned combustible mixture of gas or vapor and air to the producer, and for this purpose the pumps or other devices for feeding the elements of the mixture are controlled by an engine the operation of which depends upon that of the producer of inert gases.

Reference is to be had to the accompanying drawings, in which—

Figure 1 shows the producer in conjunction with the engine, and Fig. 2 illustrates the same parts in connection with the devices for feeding air and fuel.

To the supply chamber 4 formed in the casing 2 I admit air and gas or vapor, either mixed and through a single pipe 1 as in Fig. 1, or through separate pipes 1^a and 1^b as in Fig. 2. A partition 3 separates the

chamber 4 from the combustion chamber 5 of the producer. The combustible mixture 55 passes through the burner nozzle 6 and after being thoroughly consumed (without the admission of any additional air), passes to the place of use through the pipe 7 which is preferably in alinement with the burner 60 6 so that the path of the combustion gases will be straight or nearly so.

The combustion chamber 5 (with its inlet and outlet) and the burner 6 constitute a producer of inert gas, which is closed entirely with the exception of such inlet and outlet, that is to say, no air can reach the producer in addition to the amount fed through the pipe 1 or one of the pipes 1^a and 1^b, and the producer chamber 5 is closed 70 to the surrounding air.

It is very important that the mixture admitted to the combustion chamber 5 should have the proper constitution, since otherwise it might not burn at all, or it might be consumed insufficiently, and in either event the gas leaving through the pipe 7, instead of being an inert, non-oxidizing gas as required, would contain too large a remnant of free oxygen and would therefore not be 80 suitable for the protection of inflammable liquids. In order to test the constitution of the mixture, I have provided a tell-tale device, which in the particular construction shown consists of an internal combustion engine 9 85 which receives its motive agent through a pipe 8 branched off from the chamber 4 and connected with the valve chamber 10 from which the working medium passes to the cylinder in the usual way. The engine 90 therefore receives as its working medium, a portion of the same gaseous mixture which is fed to the combustion chamber 5. If the mixture within the chamber 4 is weakly explosive or not explosive at all, the engine 9 95 will stop and thus indicate that the producer is not working properly.

The flame at the nozzle 6 may become extinguished accidentally, and in this case the mixture (containing a relatively large proportion of oxygen) would pass unconsumed to the pipe 7. In order that the motor 9 may stop in this case also, the igniter tube 11 of the motor may be projected into the combustion chamber 5 as shown, so that ignition will not take place if the flame be-

comes extinguished accidentally or because the mixture is not sufficiently combustible. These expedients for making the operation of the motor dependent upon the proper working of the producer of inert gases, may be employed separately or jointly.

As represented in Fig. 2, the tell-tale device or engine may be utilized to operate the devices, such as the pumps 12 and 13, which 10 feed the gas or vapor and the air respectively through the pipes 1^b and 1^a. For this purpose the fly-wheel 14 of the engine may drive a countershaft 15 by means of a belt 16 and a pulley 17, and the driving pulleys 18 and 19 of the pumps 12 and 13 are connected by belts 20 and 21 with pulleys 22 and 23 respectively on said countershaft. Thus 15 air and gas or vapor will always be supplied in the same proportion, and if the mixture is not properly explosive, the motor 9 will stop, thus interrupting the feeding of the mixture and preventing the improper mixture from being forced through the pipe 7. Of course, the igniter tube arrangement 20 described with reference to Fig. 1 may be used in this case also, that is, the operation of the pumps 12 and 13 may be made dependent upon the proper ignition of the engine.

30 Certain features or combinations claimed in the present application are also shown, but not claimed, in my application No. 516974 filed concurrently herewith.

I claim as my invention:

35 1. The combination of a supply chamber, means for leading air and fuel thereto, a combustion chamber, a burner connected with the supply chamber and located within the combustion chamber, an internal combustion engine connected with said supply chamber to receive fuel and air therefrom, and an ignition tube for said engine, extending into said combustion chamber.

40 2. The combination of a supply chamber having two outlets, a burner connected with one of said outlets, a combustion chamber in which said burner is located, an internal combustion engine connected with the other outlet, an ignition tube for the engine, extending into the combustion chamber, and means, driven by said engine, for conveying fuel and air to said supply chamber.

45 3. The combination of a supply chamber having two outlets, a burner connected with one of said outlets, a combustion chamber in which said burner is located, said chamber being inclosed and having an outlet through

which the inert gas produced in said chamber may be conveyed to the place of use, an internal combustion engine connected with 60 the other outlet to receive air and fuel therefrom, and means, driven by said engine, for conveying fuel and air to said supply chamber.

4. The combination of a supply chamber 65 having two outlets, a burner connected with one of said outlets, a combustion chamber in which said burner is located, said chamber being inclosed and having an outlet through which the inert gas produced in said chamber may be conveyed to the place of use, an internal combustion engine connected with 70 the other outlet to receive air and fuel therefrom, and separate feeding devices, driven by said engine, for conveying fuel and air respectively to said supply chamber in constant proportions.

5. The combination of a supply chamber 75 having two outlets, a burner connected with one of said outlets, a combustion chamber in which said burner is located, said chamber being inclosed and having an outlet through which the inert gas produced in said chamber may be conveyed to the place of use, an internal combustion engine connected with 80 the other outlet to receive air and fuel therefrom, and two rotary pumps, driven by said engine, for conveying fuel and air respectively to said supply chamber.

6. The combination of an inclosed producer chamber having an inlet for the combustible mixture, a burner located within the chamber and connected with the said inlet, an outlet for conveying the combustion products to the place of use, and imperforate 90 walls extending continuously from the inlet to the outlet so that the surrounding air may have no direct access to the interior of the chamber, thus insuring the production of an inert gas during the normal operation of the producer, movable means for feeding the combustible mixture to the said burner, an internal combustion engine, a connection for leading to said engine, as its working medium, a portion of the same mixture which is fed to the producer, and an operative connection between the engine and the said movable means, to drive the latter.

In testimony whereof I hereunto affix my signature in the presence of witnesses.

CARL MARTINI.
